Primary Examiner — Alison M Ofstun

(57) **CLAIM**

The ornamental design for a hair straightener as shown and described.

DESCRIPTION

FIG. 1 is a perspective view of a first embodiment of a hair straightener, according to our design; shown in a closed position of use;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view thereof, shown in an open position of use;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof;

FIG. 14 is a bottom plan view thereof;

FIG. 15 is a perspective view of a second embodiment of a hair straightener, according to our design, shown in a closed position of use;

FIG. 16 is a front elevational view thereof;

FIG. 17 is a rear elevational view thereof;

FIG. 18 is a right side elevational view thereof;

FIG. 19 is a left side elevational view thereof;

FIG. 20 is a top plan view thereof;

FIG. 21 is a bottom plan view thereof;

FIG. 22 is a perspective view thereof, shown in an open position of use;

FIG. 23 is a front elevational view thereof;

FIG. 24 is a rear elevational view thereof;

FIG. 25 is a right side elevational view thereof;

FIG. 26 is a left side elevational view thereof;

FIG. 27 is a top plan view thereof; and,

FIG. 28 is a bottom plan view thereof.

(Continued)

The portions of the hair straightener shown in broken lines illustrate unclaimed portions of the hair straightener and form no part of the claimed design.
